Inventor.

UNITED STATES PATENT OFFICE.

EDWIN HART, OF WATERBURY, CONNECTICUT, ASSIGNOR TO THE WATERBURY WATCH COMPANY, OF SAME PLACE.

CYCLOMETER.

SPECIFICATION forming part of Letters Patent No. 591,761, dated October 12, 1897.

Application filed May 29, 1896. Serial No. 593,637. (No model.)

To all whom it may concern:

Be it known that I, EDWIN HART, of Waterbury, in the county of New Haven, and in the State of Connecticut, have invented certain new and useful Improvements in Cyclometers; and I do hereby declare that the following is a full, clear, and exact description thereof, reference being had to the accompanying drawings, in which--

10 Figure 1 is a perspective view of my cyclometer shown as applied to a bicycle. Fig. 2 is a like view of the same with the casing removed. Fig. 3 is a view in longitudinal section of the complete cyclometer. Figs. 4 and 5 are respectively sections on the lines xx and yy of Fig. 3. Fig. 6 is a detail perspective view of the spring-pawls for the index-wheels, and Fig. 7 is a detail view in section of the tappet I use.

20 Letters of like name and kind refer to like parts in the several figures.

The object of my invention is to provide a simple and accurate cyclometer or register for use more especially with bicycles; and to this end said invention consists in the construction and combination of parts, substantially as and for the purpose hereinafter specified.

30 In the carrying of my invention into practice I employ a frame or support for the operative parts of my cyclometer that consists of a horizontal base-plate A and two vertical arms a and a at the ends thereof. Supported by said arms is a shaft or rod B, upon which, 35 side by side, are placed a series of index or registering wheels C and C, the periphery of each of which bears numerals from "1" to "0," the first wheel of the series indicating tenths, the second units, the third tens, &c.

40 Mounted loosely upon the rod B, between the tenths-index and the adjacent arm a , is a pinion D, that is adapted to be engaged and moved by a tooth e upon the inner end of a shaft E, which is journaled directly below the 45 rod B in a bearing a' on said arm a and upon its outer end carries a star-wheel F, whose teeth are adapted to be engaged by a tappet placed upon one of the spokes of a bicycle-wheel.

50 At the side of and rotating with the gear-wheel D is a disk G, that on its side adjacent

to the tenths-index C has pivoted to it a pawl g , which is adapted to engage with a ratchet-wheel H, secured to the side of said tenths-wheel C, and when so engaged to cause the 55 turning of the latter. A spring I, attached at one end to the pawl and bearing at its other end against a pin projecting from the disk G, tends to normally swing the pawl away from the ratchet-wheel H. It is designed that for 60 each revolution of the disk G the tenths-index C shall be rotated one-tenth, and to effect this the pawl is thrown at the proper time into engagement with the ratchet-wheel H against the stress of the spring I. A pin 65 or stud K, attached to and projecting up from the plate A in the path of the pawl and engaging the same as it is carried along by the disk G, constitutes the means by which the pawl is placed in engagement with the 70 ratchet-wheel. As soon as the pawl, by the rotation of the disk, is carried out of contact with the pin or stud K, the spring I acts to disengage the pawl and wheel. A precisely similar arrangement of disk, pawl, and pin, such 75 as is employed to communicate motion from the pinion D to the first or tenths index, is used to carry or transfer from the latter to the units-disk, and so on throughout the series from the lower to the next higher. 80

The periphery of each index-disk G is provided with a series of concave notches g' and g'' , corresponding in number to the numerals on the indexes, while the periphery of the disk carried by the pinion has nine of said 85 notches, and adapted to coöperate with the notched periphery of each disk to hold the same to the point to which it may be moved is a spring finger or pawl l , that is attached to and projects up from a plate L, fastened to 90 the base-plate A. The pressure of the spring-pawl upon the notched disk while sufficient to prevent accidental turning is not so great as to seriously impede the revolution of the disk at the proper time. It will be observed 95 that all of the registering mechanism is mounted upon the base-plate A. Said mechanism, with of course the exception of the star-wheel, is housed in a casing M, whose bottom, sides, and ends are flat, but whose top is semi-cylindrical, and in the top are provided the 100 sight-openings for viewing the indexes. Said

openings, as shown, are formed by a longitudinal slot m in the casing, over which is placed a plate N , having a number of slots n and n' , one for each index, a piece of isinglass O or 5 other transparent medium being secured between said plate and the casing-top.

The registering mechanism is placed within and removed from the casing by making one end of the latter removable, and said end is 10 preferably attached to a frame-arm a . When within the casing, said mechanism is secured by means of two screws P and P' , that pass through the casing-bottom into the base-plate A . As the connecting means consists simply 15 of screws, it will be seen that the removal and replacement of the entire registering mechanism is a very easy thing.

To distinguish the numerals on the tenths or fraction index from those on the other index, I mark such numerals in sharply-contrasting colors, preferably using red on the 20 tenths-index and black on the others.

Fastened to the under side of the casing M is a bar or rib Q , that extends lengthwise of 25 the same and is provided with a longitudinally-extending slot q . Engaging said rib is a **U**-shaped clamp or holder R upon the upper end of a bracket S , that is adapted to be fastened in the customary way to the axle of 30 the bicycle-wheel and thus support the cyclometer in position to be actuated by said wheel. A screw T , passing through holes in said clamp and through the slot in the rib, and a nut U are the means for holding said 35 parts together. The slot enables the position of the cyclometer to be shifted toward or from the wheel, as may be required.

The tappet for engaging the star-wheel consists of two bars V and V' , that are clamped 40 to the spoke of the wheel by screws W and W' on opposite sides of the spoke, the former of which bars has an end projecting beyond the other that strikes the teeth or points of the star-wheel. The inner sides of the two bars 45 that engage the spoke are grooved to fit the latter, and as the wheel-spoke is commonly

arranged to extend in a tangential and not a radial line such grooves are inclined to compensate for this, so as to enable the tappet end to fairly strike the star-wheel tooth. 50

It is thought the operation of the registering mechanism has been made sufficiently clear in describing its construction to render further description unnecessary.

My cyclometer is small and compact, and 55 owing to the duplication of parts in the registering mechanism can be cheaply manufactured.

By making the index-numerals of the tenths or fractions of a mile in a color contrasting 60 with the markings of the complete miles it will be seen that no confusion in reading the registration can occur, as might be the case were the numerals of all of the index-wheels similarly marked. 65

Having thus described my invention, what I claim is—

1. In a registering mechanism, the combination of a base-piece having arms, a rod or shaft supported by said arms, a series of 70 wheels journaled on said rod or shaft, a shaft carrying a driving-wheel, supported by one of said arms, a casing side attached to said arm, and a casing within which all of the mechanism mounted on the base, except said 75 driving-wheel, is inclosed, such mechanism being removable from the casing through an opening that is closed by the casing side attached to the base-piece arm, substantially as and for the purpose specified. 80

2. A tappet for cyclometers consisting of two spoke-engaging bars, and screws to clamp said bars on the spoke, the sides of the bars that engage the spoke having inclined grooves, substantially as and for the purpose described. 85

In testimony that I claim the foregoing I have hereunto set my hand this 15th day of May, 1896.

EDWIN HART.
